UNITED STATES PATENT OFFICE.

WILLIAM H. EDMUNDS, OF BALTIMORE, MARYLAND.

LUBRICATING ATTACHMENT.

1,371,151.

Specification of Letters Patent. Patented Mar. 8, 1921.

Application filed December 4, 1919. Serial No. 342,401.

To all whom it may concern:

Be it known that I, WILLIAM H. EDMUNDS, a citizen of the United States, residing at Baltimore, State of Maryland, have invented certain new and useful Improvements in Lubricating Attachments, of which the following is a specification.

The present invention relates to improvements in lubricating attachments for internal combustion engines, the purpose of which is to automatically maintain a constant oil level in the engine crank case from which the oiling system derives its circulation supply.

To best comprehend the objects of my improvements it may be explained that in certain types of motor vehicles, it is necessary to repeatedly and frequently replenish this supply to maintain a sufficient quantity of oil to insure against depletion to a point of danger or exhaustion, but this either leads to over lubrication with its disadvantages of quick carbonization, or likelihood of running low of the supply in the event it is not constantly watched. In other words, it is known that too much oil is just as unsatisfactory as too little, and the tendency is to neglect this all important requirement of proper lubrication because it naturally involves disagreeable and dirty work.

What I aim to accomplish is to provide means whereby a reserve supply will constantly feed to the main supply just as, and only as, it is required to maintain the latter constant, and to insure that the oil level will be at the lowest point consistent with affording a sufficiency without running into the disadvantages above referred to of under- or over-lubrication.

Ancillary to the above ends, it is my object to prevent the feeding of the oil when the vehicle is not in operation and further, to eliminate likelihood of accidental escape from the reserve to the main supply when, owing to movement of the vehicle, this would become possible by reason of the uncovering of the air control port which liberates the feeding action in this type of lubricating systems.

I have had in mind, in addition to the foregoing, the desirability of providing an

article which will readily adapt itself for attachment without requiring modification of the equipment of the motor vehicle as manufactured or supplied to the trade, and one which is capable of adjustment so as to maintain that constant level which is desired for the particular motor or best suited to the needs of the vehicle, all of which will become apparent by reference to the following description, and the mechanism illustrated in the accompanying drawings in which:

Figure 1 is a fragmentary sectional view of a motor vehicle showing my appliance in operative position thereupon.

Fig. 2 is a sectional view of the reserve supply reservoir.

Figs. 3 and 4 are horizontal sectional views on the lines 3—3 and 4—4, respectively, of Fig. 2.

Fig. 5 is a sectional view of the oil gage portion, enlarged, the oil tube being shown in dotted lines.

Figs. 6 and 7 are sectional views on the lines 6—6 and 7—7, respectively, of Fig. 5.

Fig. 8 is an enlarged sectional view showing more clearly the connection with the base of the crank case and the drain plug therefor.

Fig. 9 is a sectional view, enlarged, on the line 9—9 of Fig. 5.

Fig. 10 is a sectional view on the line 10—10 of Fig. 7 and

Figs. 11 and 12 are detail side and end views, respectively, of the gage carrying nipple used with this appliance.

Throughout the following detail description and on the several figures of the drawings, similar parts are referred to by like reference characters.

It should be explained at this point that this invention is designed to be applied to the well known Ford automobile in which the crank case contains a suitable supply of lubricant that is distributed to the motor by the splash system. The crank case is always provided with two petcock openings which serve as a guide to the operator to determine the quantity of oil to be maintained in the said crank case, the lower petcock opening representing the lowest level to which the supply should be allowed to fall, while the

higher or upper of said openings represents the point beyond which the supply would be excessive. The instructions usually are that the supply be maintained between these two points but this arrangement is located at such an unhandy place that the maintenance of a proper supply is more or less neglected. The ideal condition for the best service in a motor vehicle is where the oil level is maintained constantly at the lowest point for effectiveness of operation of the lubricating system but with the conventional equipment upon the machine this is entirely impracticable and hence my invention is particularly designed to render this feasible, being automatically operable so as to require little or no attention on the part of the operator.

Referring to the drawings, 1 designates the crank case into the lower petcock opening of which I screw an externally threaded nipple 2, referring to Fig. 6, this being locked by means of the bushing nut 3. Upon this nipple I mount that portion of my apparatus which I term for the purpose of this description the gage, this consisting of the metal tube 4 which is of suitable diameter and length and provided at one side with a hollow boss 5 which freely fits over the threaded nipple 2 referred to. The passage 2' of the nipple is placed in communication with the interior of the tube 4 by the lateral opening 2" in the nipple and the passage 2^a through the side of the tube 4 so that oil may flow from the crank case through these passages, or from the gage into the crank case in the reverse direction. I utilize the upper crank case opening of the conventional equipment to assist in supporting the gage in the position most clearly shown in Fig. 5, and for this purpose, as shown in Fig. 9, a threaded stud 6 is screwed into the opening and secured by a clamping nut 7. An open or clamping collar 8 freely engaging about the tube 4 is slipped upon this stud 6 and a nut 9 is then screwed upon the stud to clamp the collar about the gage so as to hold the latter in rigid position upon the crank case. It will be noticed that the collar opening is formed so as to permit of its proper engagement with the gage regardless of the slight variation in the angle at which the opening in the crank case is made with respect to the lower opening in said crank case, there usually being some slight variation. Into the lower end of the gage tube 4 I screw the plug end of a short pipe 10, this pipe terminating at its other end in the collar 11 provided with an internal annular groove 12. Through this collar the hollow plug 13 is passed and screwed into the opening at the base of the crank case adjacent to the periphery of the fly wheel of the engine, this opening in the crank case being

for the purposes of drainage of the oil therefrom. It should be noticed that the plug 13 extends into the sediment chamber 14 a sufficient distance to permit the sediment to settle in said chamber around the plug, which latter is provided with a small closing plug 15 which may be removed whenever it is desired to drain the crank case without detachment of the gage. The annular groove 12 always insures communication between the pipe 10 and the interior of the plug 13 through a lateral opening 13' which may be positioned at any point determined by the tightening of the plug in place against leakage.

Into the upper end of the tube 4 which is provided with a hollow plug 16, internally threaded, I screw the adjustable terminal 17 of an air conduit or tube 18. This terminal, as will be observed in Fig. 5, is provided with external threads for a suitable distance to obtain a wide range of adjustment and the lower end of the terminal carries a series of baffles or disks 19 attached to the terminal off center, as clearly shown in Fig. 6, the terminal being bent as indicated at 20. In carrying out this arrangement, the diameter of the baffle disks is slightly less than the interior of the gage tube 4 and owing to this arrangement the oil passes with difficulty by the baffles, for purposes herein-after more particularly pointed out. When the terminal 17 is positioned at the proper point the clamping nut 21 is tightened against the plug 16 and the adjustment just referred to is what determines the constant oil level in the crank case, the lower end of the terminal providing the controlling air port which prevents the flow of oil to the crank case or gage when it is sealed by the liquid therein as will later be explained.

In conjunction with the gage end of the appliance just described I employ a reserve supply reservoir which may be conveniently located at any point on the vehicle at a higher level than the gage referred to. In the preferred embodiment I have illustrated this reserve reservoir as attached to the dash of the vehicle beneath the engine hood, as indicated at 22. The receptacle may be of any material but that form of the same shown in the drawing consists of a glass body 23 secured between the top 24 and the bottom 25.

This reservoir is provided with a removable closure plug 26 to permit of the filling of the receptacle with a desired amount of the lubricant and a float 27 may be provided, when the body 23 is either metal or glass, to aid in the filling of the receptacle, this float being held in the position shown in Fig. 2 of the drawings by engagement with the filler plug 26. The air tube 18 from the gage enters at the top of the reservoir 22 so as to extend into

the air space above the supply of lubricant. From the bottom of the receptacle the oil supply pipe 28 extends downwardly to the elbow 29 which enters the lower end of the 5 gage tube 4 as shown in Fig. 7. In this oil conduit I introduce a cut-off 30 provided with a valve handle 31 and this handle is connected by a cable 32 to the arm 33 which is attached to the shaft 34 of the vehicle, 10 which carries the emergency brake lever 35. The valve is thereby operable by a movement of the brake lever whenever said lever is employed to control the movement of the vehicle, this lever being always employed 15 to lock the vehicle when it stops. Whenever said lever is moved forwardly to release the brakes the cut-off, which is closed by the lever in its rearward movement, is opened through the action of a spring 36 20 which is connected to the arm 31 of the cut-off and to the base of the reserve supply reservoir 32 or any other convenient point. It should be noted that the conduits 18 and 25 28 are flexible and of sufficient length to permit of the attachment of the device to the vehicle with a reasonable range of latitude in accommodating the two main parts hereinbefore described.

While it is not an essential portion of my 30 appliance, I nevertheless make provision for the use of a sight glass in connection with the gage above described and this is designed to enable the operator of the vehicle to observe, if he so desires, whether the 35 apparatus is working correctly and thus to give him confidence in the automatic control of the lubricating system employed by him. The sight glass, indicated at 37 is of the ordinary conventional type and is connected to the end of the threaded nipple 2 40 as shown in Fig. 7 by the connector 38. When this glass is not employed the end of the nipple 2 is closed by means of a small screw plug 2^b. The connector 38 is formed 45 as shown in Figs. 11 and 12 most clearly, so as to enable the sight glass 37 to be arranged in a true vertical position, regardless of any inclination of the nipple 2 caused by the inaccuracy of boring or threading 50 the petcock opening of the crank case. To firmly clamp the gage upon the threaded nipple in the manner hereinbefore described a bushing nut 39 is secured upon the nipple as shown in Fig. 6, and this firmly holds 55 the apparatus in place just in the rear of the enlargement of the crank case accommodating the fly wheel. I purposely dispose this portion of my apparatus in close proximity to the crank case at this position 60 to insure against likelihood of its being struck by an object over which the machine might run.

In the use and operation of this apparatus it will be understood that the reservoir 22

is filled with a supply of lubricant after the proper amount is introduced into the crank case and when the motor vehicle is to be operated the brake lever 35 is moved forwardly to release the brakes. This opens the cut-off 18 and allows the lubricant to flow by the pipe 28 to the gage 4. The flow of the oil to the gage, however is controlled by the adjustable terminal 17 of the air tube 2, the lower baffled extremity of which is designed to be so adjusted in the tube 4 that its mouth will represent the predetermined oil level which it is desired to maintain. When the oil supply in the crank case falls below the end of the tube, atmospheric pressure is admitted into the tube and into the air chamber above the lubricant in the supply reservoir 23, thereby permitting the oil to run into the gage until the mouth of the air tube is closed. The atmospheric pressure is obtained by admitting the air from the crank case through the threaded nipple 2, or the gage tube 4 may be provided with an opening at its upper end for this purpose. To produce a modification of the oil level, if such is required, it is only necessary to raise or lower the terminal 17 in an obvious manner. But to best serve the purposes of the invention and to obtain the best results the oil level should be maintained at the lowest possible point, that is approximate 95 at the lower crank case opening in the particular type of vehicle herein described.

Owing to the inclination at which the gage is arranged, as shown in Fig. 5, I preferably form the end of the air tube with the bend as indicated at 20, so that the opening will lie at the lower side of the tube 4. It would only be necessary to, rotate this terminal 17 to shift this bent portion of the tube to accomplish a raising of the oil level, this being an incidental feature of the arrangement as provided.

It will be understood that in motor vehicles, the oil is more or less subject to sloshing when traveling over rough, uneven ground and in known device of the character of this invention this leads to the disadvantage of accidental uncovering of the air port or mouth of the air tube 17. When this takes place the oil is permitted to run into the gage and the crank case and the oil level is thus raised beyond the predetermined point. To prevent as nearly as possible such accident occurring in this arrangement is the purpose of the use of the baffles 19 which tend to eliminate the sudden movement of the oil in the manner specified and the uncovering of the air port.

It is further quite well known that in motor vehicles of this type where the fly wheel operates in the oil sump to produce a proper circulation that the oil is thrown from the fly wheel portion of the crank case,

- thereby lowering the oil level at this point where the gage is attached. This would affect the proper operation of a constant level oil gage of this type unless provision is made to prevent this from occurring. For this reason I arrange the entrance pipe 10 at the base of the fly wheel portion of the crank case adjacent to the periphery of the fly wheel where a sufficient pressure is produced by the centrifugal action of the oil thrown by the fly wheel to force the oil into the lower end of the gage tube 4 so that the level of the oil does not fall, in my apparatus, away from the entrance of the air tube even when the level in the sump is lowered by the operation of the engine. The arrangement of my appliance is therefore such that the oil level may be maintained at the low point found desirable under all conditions. It should be understood, however, that I do not depend entirely upon the centrifugal action of the fly wheel to maintain the oil supply in the gage tube 4 because of the fact that the tube 10 connects with the lowest point of the crank case and naturally the oil in seeking its level will stand in the gage tube in accordance with the level in the fly wheel portion of the crank case.
- 30 When the motor vehicle is brought to a stop the emergency lever 35 is drawn rearwardly, which closes the cut-off 30 and precludes the flow of oil from the reserve tank when the vehicle is standing still. Under such conditions the appliance is completely automatic and requires little or no attention on the part of the operator other than the maintenance of a sufficient supply of oil in the reserve reservoir.
- 40 Having thus described my invention, what I claim as new is:
1. In lubricating apparatus of the class described, the combination with an engine crank case, of a lubricant supply reservoir at a higher level, an oil conduit establishing communication between the reservoir and the crank case, an air tube arranged to admit air to the reservoir and thereby allow feeding of the lubricant, said tube having an adjustable terminal adapted to be disposed with its entrance at the proper height with respect to the crank case lubricant at which the level of said lubricant is to be maintained so as to be closed by said lubricant, and inclosing means in which said adjustable terminal is disposed and having communication with the crank case at a point to receive oil under action of the engine fly wheel.
  - 60 2. In lubricating apparatus for internal combustion engines, the combination with a crank case adapted to hold a supply of oil and having an opening arranged approximate the point of safety for the oil level

therein, of a gage device constituting an attachment for said crank case connecting at an intermediate point in its length with the crank case through said opening, an oil reserve supply chamber arranged at a higher level, an oil conduit establishing communication between the reserve supply and the crank case through the opening aforesaid, an air tube connected at one end with the reserve supply to admit pressure thereto and having its lower end adjustably mounted in the gage for maintaining the oil level in the crank case at a predetermined level, and a separate oil passage between the gage and the crank case to admit oil therefrom for closing the air tube outlet.

3. A lubricating attachment for internal combustion engines for maintaining a constant level of oil in the crank case comprising a stand tube, a nipple connecting said tube to the crank case, an oil reserve supply chamber adapted to be arranged at a higher level than the crank case and connecting with the stand tube, an air conduit between the chamber and the stand tube into which the air conduit extends, and baffle means on said conduit preventing sudden movement of the oil past the mouth of the conduit.

4. A lubricating attachment for internal combustion engines for maintaining a constant level of oil in the crank case comprising a stand tube having an opening establishing communication with the crank case at approximately the low point of safety of maintenance of the oil level therein, means engaging said stand tube to firmly hold the same upon the crank case, a conduit connecting the end of the stand tube with the drain outlet of the crank case, an oil reserve supply chamber arranged at a higher level, an oil conduit intermediate said reserve chamber and the stand tube, a cut off in said oil conduit, manually operable means connected with the cut off to close the same when moved in one direction, means for automatically opening the cut off when said manually operable means is moved in the opposite direction, and an air tube intermediate the oil reserve chamber and the stand tube including a threaded terminal extending into the stand tube and adjustable longitudinally thereof to provide for modification of the predetermined oil level.

5. A lubricating attachment for internal combustion engines for maintaining a constant level of oil in the crank case comprising a stand tube having a hollow boss projecting from one side, a threaded nipple adapted to be connected to the crank case and extending into said hollow boss for establishing communication between the crank case and the stand tube, means on said nipple for clamping the tube in position upon

the crank case, a retaining collar supported by said crank case and engaging with the tube to hold the latter in position upon the crank case, a conduit extending from the 5 base of the stand tube to the drain opening of the crank case, means for holding the end of the conduit at the drain opening and establishing communication between said opening and the crank case, an oil reserve

supply reservoir disposed at a higher level 10 and having a passage establishing communication with the stand tube, an air tube extending from the stand tube to the oil reserve reservoir, and means in said air passage for cutting off the supply of oil to the 15 stand tube.

In testimony whereof I affix my signature.
WILLIAM H. EDMUNDS.
